COMBINATION MANOMETER AND VARIABLE RELIEF VALVE

Bruce B. Miller, Eaton Rapids, Mich., assignor to Neo-Care, Inc., Eaton Rapids, Mich.

Filed Nov. 24, 1972, Ser. No. 308,966

Term of patent 14 years

Int. Cl. D24—99, 02; D23—01
U.S. Cl. D83—12 R

FIG. 1

FIG. 4

FIG. 2

FIG. 3

FIG. 5

FIG. 6

FIG. 1 is a perspective view of a combination manometer and variable relief valve showing my new design;
FIG. 2 is a side elevational view thereof;
FIG. 3 is a right end elevational view thereof;
FIG. 4 is a left end elevational view thereof;
FIG. 5 is a top plan view thereof; and
FIG. 6 is a bottom plan view thereof.

I claim:

The ornamental design for a combination manometer and variable relief valve, as shown.
